Fig. 5

FIG. 1 is a top view of a combined pencil case and spelling device embodying my new design;

FIG. 2 is a front elevational view of the design as shown in FIG. 1;

FIG. 3 is a rear elevational view thereof;

FIG. 4 is an end elevational view thereof looking in the direction of the arrows 4-4 on FIG. 1, the end opposite thereto being similar in appearance; and

FIG. 5 is a top perspective view thereof as it appears with the cover in open position.

The essential features of my design reside in the portions shown in solid lines on the drawings.

I claim:

The ornamental design for a combined pencil case and spelling device, substantially as shown and described.
